Huron & Huron

UNITED STATES PATENT OFFICE.

PERCY J. BAKER, OF MALVERN, PENNSYLVANIA.

CHAIN FASTENER.

1,427,572.

Specification of Letters Patent. Patented Aug. 29, 1922.

Application filed May 19, 1920. Serial No. 382,468.

To all whom it may concern:

Be it known that I, PERCY J. BAKER, a citizen of the United States, residing in Malvern, Chester County, Pennsylvania, have 5 invented a new and useful Chain Fastener, of which the following is a specification.

My invention relates to fasteners for anti-skid chains and the like, and the object of my invention is to provide a fastener comprising certain novel and improved features 10 hereinafter fully described.

In the attached drawings:

Figure 1, is a vertical section of a fastener made in accordance with my invention;

15 Fig. 2, is a plan view of the fastener shown in Fig. 1;

Fig. 3, is a vertical section illustrating my fastener in the open position, and

20 Fig. 4, is a perspective view of the body portion of the fastener.

With reference to the drawings, the fastener comprises a body portion 1, to which is pivotally secured a retaining member 2.

The body member 1 consists of two substantially parallel side portions 3 and 4 secured together in the present instance along one side thereof by a rounded substantially tubular portion 5 forming at the rear of the said walls an internal chamber 6. The said side

30 portions 3 and 4 of the body member have oppositely, and in the present instance diagonally, disposed recesses 7, 7 and 8, 8 extending backwardly from the front adjacent edges thereof, in which recesses a link

35 of a chain may be inserted in the manner illustrated in Fig. 1. The inner ends of the said slots 7 and 8 are preferably rounded out to form a seat for the said chain link occupying the recess.

40 The retaining member 2 is, in the present instance, pivotally mounted between the walls 3 and 4 of the body member 1 upon a pin 9, said pivot pin being located at a point near the outer and lower edges of the said

45 walls. The said retaining member is substantially flat and thin throughout, so that when moved inwardly it may pass between the said walls and be substantially enveloped thereby, the main body portion 10 of the

50 member lying just within the outer edges of the side portions and across the outer ends of the slots 7 and 8 whereby the latter are closed and the link occupying either of the said slots prevented from slipping out. At

55 the lower end of said retaining member is an arm 11 extending substantially perpen-

dicularly from the body portion 10, and the said walls 3 and 4 of the body member are apertured at 12, 12 for the reception in the present instance of a bolt or pin 13, to which is secured the end link 14 of a chain, the base of the apertures 12, 12 being so located that they register with a recessed seat 15 in the upper edge of the said arm 11 when the fastener is closed, as shown in Fig. 1. 60 The bolt 13 thus tends to prevent the opening of the fastener so long as there is any tension upon the chain. The apertures 12, however, are elongated, and when it is desired to open the fastener by pulling the said 65 retaining member from between the walls of the body member, the bolt 13 may rise upwardly through the aperture to permit the upward movement of the arm 11 as the said retaining member is rotated outwardly on its 70 pivot.

As clearly shown in the drawings, the end of the arm 11 beyond the seat portion 15 slopes diagonally downward towards the end, this formation permitting the opening 80 of the retaining member sufficiently to release the chain from the recesses 7 or 8, or to insert the links of the chain therein.

The main portion 10 of the retaining member 2 is comparatively narrow, and has 85 extending outwardly near the top thereof two arms 16 and 17, substantially hook-shaped in the present instance, which are adapted to overlie the rounded-out inner ends of the slots 7 and 8. These arms 16 and 17 are of such length that the extremities thereof, when the fastener is closed, extend beyond the edges of the side portions 3 and 4 which lie opposite the recessed edges thereof and, in the present instance, into the 90 chamber 6 formed by the portion 5, and the said extremities are provided with resilient 95 means for engaging the edges of the said side portions to prevent accidental withdrawal of the retaining member from the body.

In the present instance the retaining member 2 is made of a resilient metal, and the ends of the arms 16 and 17 are divided, the divided portions or toes 16^a and 17^a of the 100 said arms being spread slightly apart, as is 105 most clearly shown in Fig. 1.

The outer edges of the side portions 3 and 4 are preferably slightly splayed to accommodate the spread ends of the arms 16 and 17 as the member 2 enters the body portion, but 110 at the rear the said side portions are so close together that the spread ends are con-

tracted, but when the ends of the arms finally enter the chamber 6 they are permitted to spread apart and thus offer a resistance to withdrawal through the comparatively restricted opening between the said rear edges of the side portions.

Thus, in addition to the locking action obtained through the arm 11 at the bottom of the retaining member, there is the locking 10 means upon the arms 16 and 17 at the top of the said member, which renders the fastener completely safe.

It is clear that there may be numerous modifications in the form of the fastener 15 with no departure from the essential features of the invention.

I claim:

1. In a fastener, the combination with a body member comprising two substantially 20 parallel side portions having oppositely disposed recesses therein, of a retaining member pivotally secured to said body and adapted to be inserted between the said side portions from the recessed side thereof to close said 25 recesses, an arm upon said retaining member projecting beyond the edges of said side portions opposite the recessed edges thereof when said retaining member is in the recess-closing position, and resilient means at the outer end of said arm for engaging the edges of the side portions to prevent accidental withdrawal of said retaining member.
- 30 2. In a fastener, the combination with a body member comprising two substantially parallel side portions having oppositely disposed recesses therein, of a retaining member pivotally secured to said body and adapted to be inserted between said side portions from the recessed side thereof to close said recesses, and an arm upon said retaining member projecting beyond the edges of said side portions opposite the recessed edges thereof when said retaining member is in the recess- 35 closing position, the outer end of said arm being divided and spread laterally to form resilient toes adapted to engage the edges of the side portions and tending to prevent withdrawal of said retaining member.
- 40 3. In a fastener, the combination with a body member comprising two substantially parallel side portions having oppositely disposed recesses extending inwardly from adjacent edges thereof, said side portions being joined together at the edges opposite the said recessed edges by an enlarged substantially tubular portion, of a retaining member pivotally secured to said body and adapted to be inserted between the said side 45 portions from the recessed side thereof to close said recesses, and an arm upon said

retaining member projecting into the said tubular portion when said retaining member is in the recess-closing position, the outer end of said arm being divided and spread laterally to form resilient toes adapted to engage the edges of the side portions and tending to prevent withdrawal of said retaining member.

4. In a fastener, the combination with a body member comprising two substantially parallel side portions having oppositely disposed recesses therein, of a retaining member pivotally secured between the said side portions and adapted to close the said recesses, a lateral arm at the pivoted end of said retaining member, and elongated and oppositely disposed apertures in said side members, the lower end of said apertures registering with the upper edge of said lateral arm of said retaining member when the latter is in the recess-closing position.

5. In a fastener, the combination with a body member comprising two substantially parallel side portions having oppositely disposed recesses therein, of a retaining member pivotally secured between the said side portions and adapted to close the said recesses, a lateral arm at the pivoted end of said retaining member, elongated and oppositely disposed apertures in said side members, the lower ends of said apertures registering with the upper edge of said lateral arm of said retaining member when the latter is in the recess-closing position, 95 an arm at the upper end of said retaining member adapted when the said member is in the closing position to lie between said side portions, and resilient means carried by said last-named arm for preventing accidental withdrawal thereof from between the side portions.

6. In a fastener for chains, the combination with a body member comprising two substantially parallel side portions having oppositely disposed recesses therein, of a retaining member pivotally secured between the said side portions and adapted to close the said recesses, a lateral arm at the pivoted end of said retaining member, said arm extending inwardly between the said sides of the body member when the retaining member is in the recess-closing position, slotted apertures correspondingly located in the said sides of the body member through which a link of a chain is adapted to pass, said apertures being so located that when the chain is under tension the said retaining member is prevented from opening by engagement of the said arm with the said link, substantially as described.

PERCY J. BAKER.
